CLAIM

The ornamental design for a blender, as shown and described.

DESCRIPTION

FIG. 1 is a perspective view of a blender and jar showing my new design;

FIG. 2 is a front elevational view of the blender and jar shown in FIG. 1;

FIG. 3 is a rear elevational view of the blender and jar shown in FIG. 1;

FIG. 4 is a top plan view of the blender and jar shown in FIG. 1, a bottom plan view not being shown as it is devoid of ornamentation;

FIG. 5 is a left side elevational view of the blender and jar shown in FIG. 1;

FIG. 6 is a perspective view of the blender shown in FIG. 1, shown with the jar being omitted for ease of illustration in FIGS. 6-10;

FIG. 7 is a front elevational view of the blender shown in FIG. 6;

FIG. 8 is a rear elevational view of the blender shown in FIG. 6;

FIG. 9 is a top plan view of the blender shown in FIG. 6, a bottom plan view not being shown as it is devoid of ornamentation; and,

FIG. 10 is a left side elevational view of the blender shown in FIG. 6.

The broken lines shown in the Figures are used for illustrative purposes only and form no part of the claimed design.
